POST UNIT FOR ROOM DIVIDERS, GRILLES
OR THE LIKE

Evaline Clarke Sellors, Fort Worth, Tex., assignor to McKinley Iron Works, Fort Worth, Tex., a partnership

Filed Jan. 26, 1959, Ser. No. 54,321

Term of patent 14 years

(Cl. D13—1)

Fig. 1 is an elevation of one edge of a post unit for room dividers, grilles or the like embodying my new design;

Fig. 2 is an elevation of one side of the same;

Fig. 3 is an elevation of the other edge of the article;

Fig. 4 is a bottom view;

Fig. 5 is a top view; and

Figs. 6 and 7 are cross sectional views taken on the lines 6—6 and 7—7 respectively in Fig. 2

The dominant features of my design reside in the portions shown in full lines.

I claim:

The ornamental design for a post unit for room dividers, grilles or the like, as shown and described.
